UNITED STATES PATENT OFFICE

150,921

DESIGN FOR A DRAPERY HANGER

William F. Binsack, Irondequoit, N. Y.

Application March 12, 1947, Serial No. 137,543

Term of patent 7 years

(Cl. D21—3)

To all whom it may concern:

Be it known that I, William F. Binsack, a citizen of the United States of America and resident of the town of Irondequoit, in the county of Monroe and State of New York, have invented a new, original, and ornamental Design for a Drapery Hanger, of which the following is a specification, reference being had to the accompanying drawings, forming part thereof.

Fig. 1 is a top plan view of a drapery hanger, showing my new design;

Fig. 2 is a front elevational view of the same; and

Fig. 3 is an end elevational view of the same.

I claim:

The ornamental design for a drapery hanger, substantially as shown.

WILLIAM F. BINSACK.
